UNITED STATES PATENT OFFICE.

CHARLES LINKE, OF PARIS, FRANCE.

ATOMIZER FOR LIQUIDS.

Application filed August 15, 1923. Serial No. 657,532.

To all whom it may concern:

Be it known that I, CHARLES LINKE, residing at Paris, France, a citizen of the French Republic, have invented or 5 covered certain new and useful Improvements in Atomizers for Liquids, of which improvements the following is a specification.

My invention relates to improvements in 10 atomizers for liquids, and particularly to atomizers whose essential feature is a member rotating at high speed. I have applied my invention in the construction of burners for the consumption of liquid fuel and in 15 that application I shall describe it. But the applicability of the invention in a wider field of utility will be recognized.

In the accompanying drawings Fig. I is a fragmentary view of an actual assembly, 20 showing partly in axial section and partly in elevation the structure in which my invention centers. Fig. II is a view of the same structure in side elevation. Fig. III shows in two fragmentary views, in section 25 and in elevation, a detail of structure. Fig. IV is a view in side elevation of the assembled burner in one form. Fig. V is a view of it in another form, and illustrating a minor variation. Fig. VI is a 30 fragmentary view corresponding to Fig. I, and illustrating a modification hereinafter to be explained.

The invention consists, first of all in a fixed member, which takes the form of a 35 cylindrical cup. The axis of this cup coincides with that of the rotating disk. The disk is provided on either side with a plate of suitable thickness, whose edges are folded back in such manner as to form a 40 circular canal. From this canal lead orifices the number of which may be varied. These orifices in cross-section are not uniform through the plate, from side to side; but they flare, enlarging in diameter as they 45 approach the disk, in such manner as to form openings in the shape of a truncated cone, or approximately such, the large base of the frustum being toward the disk.

Above each of the so-formed openings, 50 a small plate is arranged in any suitable manner. It may, for example, be formed of metal and soldered along one edge to the larger plate, and along its opposite edge pressed against the disk.

55 The operation of mechanical dissociation begun in the circular canal is continued in

these openings. The very slender jet of liquid strikes forcibly upon the small plate and is broken into very fine particles. These escape on either side and spread upon the 60 disk, and there the operation of subdivision or atomization is completed.

The liquid to be atomized flows from each of the cups across an annular slit several millimeters in extent, formed on one side 65 by a sort of crown whose rim is oblique to the axis of rotation, and on the other side by a circular slab, the edges of which have the same obliquity as the rim of the crown. The two slabs by suitable means 70 of assembly hold the plates secure, and all these parts rotate in unison with the disk.

Each cup, though closed, is provided in its side walls with orifices, to give passage 75 to a ring which hangs within the casing, and into a pool of liquid within the casing. By such means liquid, responsive to its nature is entrained. Instead the liquid may of course be introduced into the cups 80 through suitable conductor tubes.

Instead of a ring depending into a pool of liquid, a chain may be provided, by means of which liquid may be carried for some distance, to the casing within which the disk 85 together with the above-mentioned improvements is enclosed. In that case the chain may be driven from the same shaft as the disk, and it will suffice to remark that a system of speed reduction should then be 90 interposed.

It is possible, by way of variation, to provide a cup on one side of the disk only. The liquid to be atomized will in that case gain access to the side of the disk which lacks a cup, by means of openings pierced 95 through the disk similar to and alternating in position with those formed in the plate which is arranged on the opposite side of the disk. These openings too will be covered over with small metal plates such 100 as those already described, and their role will be precisely the same.

These improvements may be applied, whenever a liquid is to be atomized, and the motive power required for their operation will not at all exceed that employed 105 in atomizers hitherto in use.

I shall, in exemplary way, describe the improvements in their application to a liquid-fuel burner.

Referring, first, to Fig. I of the drawings, upon the shaft *a* the disk *b* is mounted.

Plates c, c' are arranged upon opposite sides of the disk. Their margins are bent back in suitable manner, to form, as has been explained above, a sort of circular canal d, d' .
 5 At the periphery of each of the plates c, c' and adjacent disk b the orifices e, e', e'' , etc. are arranged; and to them, as has been explained, such form is given that the liquid delivered through these orifices under centrifugal force makes impact upon the small plates p, p' . The jet then is spread upon the disk b from each side of the little plate in the form of finely divided particles, and these spread fan-like over the disk as they 10 approach its periphery.

Each of the plates c, c' is in this instance secured by a slab f, f' . One of these slabs is formed in one piece with the hub which carries the disk, the other forms a companion piece, cooperating with the first in effecting assembly. Rivet-holes g, g' are formed in these slabs f, f' , to receive rivets, when these means are employed for securing the entire assembly.
 20

25 The slabs f, f' are circular and their edges are cut in such manner as to form an inclined plane, defining the circular slit through which the combustible liquid finds exit from the cup.

30 The cups h, h' themselves which hold the liquid are suitably mounted upon the shaft, a . They terminate in a sort of crown, i, i' , inclined to the axis of rotation in correspondence with the inclined edges of the slabs f, f' , and in the assembly these inclined edges of the cups stand opposite the inclined edges of the slabs, and between slab and cup-rim a circular space or slit is formed of several millimeters extent, 35 through which the combustible liquid escapes in order to reach the canal formed in each of the plates c and c' and orifices e, e' , opening from the canals.
 40

45 In Fig. III the minute configuration is indicated of the orifices e, e' , through which the combustible liquid when confined within the circular canals d, d' escapes to the surfaces of the disk. A part only of the plate, bent back as indicated at k , is shown in Fig. III. The orifices are formed in suitable number. They are formed at the periphery of the plate and at the base of the bent-back margin, and by virtue of the shape given them, a shape indicated in Fig. 50 III, the combustible liquid is projected in fan-like spread upon the disk.
 55

60 Grooves m, m' are formed in the hub. In these grooves rest rings s, s' . Resting in these grooves m, m' , the rings s, s' depend into a pool of combustible liquid maintained in a suitable manner in the casing n , within which the disk turns. In Fig. I the rings s, s' are shown in cross-section in their position in grooves m, m' . In Fig. 65 IV the position of these rings is indicated

by the dotted circle s . In Fig. I orifices x, x' through the side walls of the cups are indicated through which the rings when in place may extend. The cups h, h' are not rotated. It is the axle a with its hub which 70 is rotated. The orifices x, x' , indicated in Figure I are, as will be apparent, adequate to permit the passage therethrough of the rings s, s' , and to permit the functioning 75 of these rings in the manner described.

It may be that, with safety in view, or to meet restrictions imposed, the reservoir of combustible liquid should be entirely separate from the casing in which the disk turns. In that case an arrangement such 80 as that shown in Fig. V may be adopted. Here a reservoir of combustible fluid is contained within a separate casing w , and a chain o , travels within a suitable duct to carry fluid from the reservoir to the casing n , within which the disk turns. The chain 85 may of course be driven, as has been said, directly or indirectly from the shaft which carries the disk.

The more deeply the ring or chain is submerged the greater will be the quantity of liquid conveyed to the cup, and any expedient within the knowledge of the engineer may be resorted to, in order to lower the surface into which the ring or chain 90 plunges.

In the case of feeding by means of a chain, as particularly shown in Fig. V, a small tube t may be provided, to limit the height to which the liquid may rise within the 100 casing n .

I have said that instead of the bilateral arrangement shown in Fig. I, I may employ a single cup. This is particularly illustrated in Fig. VI. Here there is a single cup h' provided on one side of the disk only, and correspondingly, there is a single plate c' provided on the same side of the disk with the cup h' . Alternating with the openings e , already described, are openings y , opening through the ring c itself and through the disk b as well, and to the opposite side of the disk b . Like the openings e these openings y flare from the canal formed by the recurved edge of plate c' 110 to the further side of the disk b . As is the case with the openings e , these openings y also are overhung with small plates z . By such provision the liquid from one cup may 115 be spread upon both sides of the disk b .
 120

The invention which I now have described in its application to a liquid-fuel burner will be seen to be an improvement upon the apparatus described in my two pending applications for Letters Patent of the United States, No. 468,318, filed May 10, 1921, and No. 547,424, filed May 28, 1922.
 125

I claim as my invention:

1. In apparatus for atomizing liquid the combination of a rotatable disk, a marginally 130

flanged plate concentrically mounted upon the disk and rotatable in unison with the disk, an opening piercing the plate at the base of its marginal flange and a deflector plate borne by said main plate and extending toward the surface of the disk and overhanging the said opening.

2. In apparatus for atomizing liquid the combination of a rotatable disk with thick hub portion and thin web portion, a cup mounted coaxially with said disk, the rim of the cup being beveled and cooperating with the adjacent surface of the hub portion of the disk to form a passageway for

liquid from the cup flaring outwardly and toward the thin web portion of the disk, means for gathering the liquid flowing under centrifugal force through said passageway and projecting it centrifugally in spreading jets upon the surface of the web portion of the disk, and means for supplying liquid to said cup.

In testimony whereof I have hereunto set my hand.

CHARLES LINKÉ.
